(57) **CLAIM**

The ornamental design for a refrigerated display counter, as shown and described.

DESCRIPTION

FIG. 1 is a front perspective view of a first embodiment of a refrigerated display counter showing my new design;

FIG. 2 is a front view thereof;

FIG. 3 is a rear view thereof;

FIG. 4 is a left side view thereof;

FIG. 5 is a top view thereof;

FIG. 6 is a rear perspective view thereof;

FIG. 7 is a front perspective view of a second embodiment of a refrigerated display counter;

FIG. 8 is a front view thereof;

FIG. 9 is a rear view thereof;

FIG. 10 is a left side view thereof;

FIG. 11 is a top view thereof; and,

FIG. 12 is a rear perspective view thereof.

Bottom views are omitted since the bottom views are invisible in normal use.

Right side views are omitted since the right side views are mirror images of the left side views.

1 Claim, 12 Drawing Sheets
